UNITED STATES PATENT OFFICE.

ALFRED WEBBER, OF PORTSMOUTH, ENGLAND.

TOBACCO-PIPE AND CIGAR AND CIGARETTE HOLDER.

1,373,849.

Specification of Letters Patent.

Patented Apr. 5, 1921.

Application filed April 13, 1920. Serial No. 373,665.

To all whom it may concern:

Be it known that I, ALFRED WEBBER, a subject of His Majesty the King of England, and resident of Portsmouth, in the county of 5 Hants, Kingdom of England, have invented certain new and useful Improvements in or Connected with Tobacco-Pipes and Cigar and Cigarette Holders, of which the following is a specification.

10 This invention relates to tobacco pipes and cigar and cigarette holders.

The invention has for its object to provide tobacco pipes and cigar and cigarette holders with improved, simple and inexpensive means whereby saliva and accumulated tobacco juices are positively maintained out of contact with the tobacco in the bowl of the pipe or holder, thereby keeping the tobacco dry, enabling the whole of it to 20 be smoked to a dry ash and greatly economizing the consumption of the same, whereby the stem of the pipe or holder is kept perfectly clear from small pieces of tobacco and from ash and therefore does not become 25 stopped up, and whereby, owing to the tobacco being maintained dry, the inside of the bowl or pipe or holder does not become crusted or coated with a hard deposit difficult to remove.

30 The invention refers to tobacco pipes and cigar and cigarette holders of the kind in which it has been proposed to provide a partition or false bottom supported upon an annular ledge formed inside of the bowl 35 of the pipe or holder and disposed above a chamber in said bowl.

The present invention provides a pipe or holder of the kind referred to, and is distinguished in that the partition or false bottom is non-perforated, non-absorbent and 40 removably supported upon the ledge, that the latter extends inwardly and is undercut in such manner that it serves to restrain saliva and nicotine collected within the chamber and to prevent it moving into contact 45 with the tobacco in the pipe or holder when the latter is laid on its side, and that the under side of the partition or false bottom or the upper surface of the ledge is 50 or are formed with grooves or air passages to insure a draft through the pipe.

The invention will now be described with reference to the accompanying drawings, in which:—

55 Figure 1 is a sectional elevation of the bowl and integral stem portion of a tobacco

pipe constructed in accordance with a convenient manner of carrying out the invention.

Fig. 2 is a sectional elevation on the line 60 2—2 of Fig. 1.

Fig. 3 is a detail plan view of the partition or false bottom.

Fig. 4 is a view similar to Fig. 1 of a modified method of carrying out the invention. 65

Fig. 5 is a sectional elevation on a line at right angles to the plane of Fig. 4, but with the partition or false bottom removed from the bowl. 70

Fig. 6 is a plan of the pipe shown in Fig. 4, and

Fig. 7 is a detail plan view of the partition or false bottom shown in Figs. 4 and 6.

Similar parts in all of the figures are 75 designated by like reference letters.

Thus, in carrying out the invention the bowl *a* of the pipe is formed with a horizontal, inwardly extending, annular flange or ledge *c* undercut at *c'* and disposed above 80 a chamber *d* communicating with the bore *e* in the stem *f*. A disk, partition or false bottom *h*, preferably made of the same material as the bowl of the pipe, but which may be made of any non-absorbent material 85 other than that of the pipe if desired, is of a diameter slightly less than that of the bore of the bowl, and is fitted within the bowl *a* to removably rest upon the flange *c*. In the modified form of the pipe, Figs. 4 to 90 7, the bowl *a* of the pipe is formed with a horizontal or transverse, undercut, annular groove *b* disposed above the flange or ledge *c* and the chamber *d*. Two longitudinal grooves *g* are formed down the bore of the 95 pipe bowl from the mouth of same to the annular groove *b*. The disk, partition or false bottom *h* is fitted within the bowl *a* to removably rest upon the flange or ledge *c* and in alinement with the annular groove *b*, 100 as shown in Fig. 4. Two lugs or projections *i* are formed on the periphery of the disk *h* and adapted to engage within the grooves *b* and *g* in the bowl *a*.

When it is desired to use the modified form 105 of pipe the disk *h* is slid into position down the bore of the bowl *a* to rest upon the flange or ledge *c*, the projections *i* being caused to slide within and down the grooves *g*. When in position upon the flange or ledge *c* the 110 disk *h* can be prevented from accidentally falling out of the bowl, or being otherwise

dislodged from its correct position, by partially turning it in its own plane to cause the projections *i* thereon to move out of alinement with the lower ends of the grooves *g* 5 and engage under the upper shoulder *j* of the annular groove *b*, as indicated in Fig. 6. Recesses *k* formed in the disk *h* facilitate the turning of the latter by means of a suitable tool, but the fit of the disk within the annular groove is sufficiently loose to enable it to be turned with the tip of the finger without the employment of a tool.

The hole *l* formed through the flange or ledge *c* may be of various diameters according to requirements. The stem *f* may be screw threaded as at *m*, formed with an enlarged tapered bore, or otherwise suitably shaped for the attachment thereto of the mouthpiece of the pipe. The chamber *d* 20 may be filled with cotton or wool or other absorbent material.

With the constructions of tobacco pipe above described, saliva entering the bore *e* of the stem *f* is collected within the chamber *d* which, in conjunction with the inwardly extending flange or ledge *c*, positively prevents said saliva reaching the tobacco disposed in the bore of the bowl and above the disk *h*, so that said tobacco is 25 maintained perfectly dry with the result that it can be wholly consumed to a dry ash, the consumption of tobacco is economized to a very great extent, the inside of the bowl does not become coated and caked with a hard deposit necessitating the use of a penknife or other instrument in well-known manner, and a sweet, clean dry and considerably prolonged smoke can be obtained by the use of the pipe. The disk *h* prevents 30 small pieces of tobacco being drawn into or entering the bore *e* and, in conjunction with moisture therein, choking up the pipe. When the pipe is laid on its side the inwardly extending ledge or flange *c* serves 45 to restrain the saliva and nicotin in the chamber *d* and prevent it coming into contact with the tobacco in the bowl *a*.

The disk *h* is a loose fit inside the bowl *a*, and the underside of said disk is formed 50 with grooves or air passages as at *n* in Figs. 1 to 3, or the ledge or flange *c* is provided with grooves or air passages such as indicated at *o* in Figs. 4 to 6, to allow for the

free passage of air and smoke around said disk into the bore *e* of the stem *f*, the grooves *b*, when provided, assisting the draft of the pipe. After the smoker has used the pipe and consumed the charge of tobacco in the bowl, all he need do is to shake out any collected saliva and nicotin through the stem 55 in the manner usual with ordinary pipes, and blow through the pipe to discharge the tobacco ash or dust, and this without removing the disk *h*. As will be appreciated, the bowl of the pipe does not have to be violently knocked or scraped to remove unconsumed, wet and useless tobacco. Should the disk accidentally fall out of the bowl or become dislodged it is an easy matter to replace it in its correct position.

It will be appreciated that the invention produces a pipe or holder with which the objects and advantages desired are obtained without in any way interfering with or complicating the construction of the stem 75 or mouthpiece of same as is often the case with many forms of pipes or holders heretofore made or proposed, and that a perfectly free and unobstructed stem bore is provided.

What I claim is:—

1. A tobacco pipe having the bowl divided by an annular ledge providing restricted communication between the bowl portions and opposite sides of the ledge, and an imperforate non-absorbent partition removably supported on said ledge as a support for the tobacco.

2. A tobacco pipe having the bowl divided by an annular ledge providing restricted communication between the bowl portions and opposite sides of the ledge, and an imperforate non-absorbent partition removably supported on said ledge as a support for the tobacco, there being air passages 90 formed between the ledge and partition.

3. A tobacco holding element through which smoke is to be drawn from the burning tobacco, comprising a saliva chamber divided from a tobacco chamber by an annular ledge, and an imperforate non-absorbent partition adapted to rest on said ledge as a support for the tobacco.

In testimony whereof I have hereunto signed my name.

ALFRED WEBBER.
